UNITED STATES PATENT OFFICE.

DAVID G. PERLMUTTER, OF NEW YORK, N. Y.

COMBINATION ARTICLE OF FURNITURE.

1,252,165.

Specification of Letters Patent. Patented Jan. 1, 1918.

Application filed January 5, 1917. Serial No. 140,811.

To all whom it may concern:

Be it known that I, DAVID G. PERLMUTTER, citizen of the United States, residing at New York, in the county of New York and State 5 of New York, have invented new and useful Improvements in Combination Articles of Furniture, of which the following is a specification.

This invention relates to the class of furniture and particularly convertible furniture and has for its principal object the provision of a device of this character which will include a frame structure which when adjusted to one position will serve the purpose 10 of an infant's crib, while, when adjusted to another position, will take the form of an infant's high chair and yet be capable of a still further adjustment whereby the structure can be used advantageously as an infant's swing. While the device is intended principally for use as a portable indoor structure, it is designed with the intention of permitting of its use as a lawn swing, reclining chair and bed and I therefore do 15 not wish to limit myself to the particular use to which the invention is put.

Another object of the invention resides in the construction of a device of the mentioned character which will be foldable 20 whereby it can be arranged in a comparatively compact package for shipment or storage.

With the above and other objects in view which will appear as the nature of the invention is better understood, the same consists in the improved construction and novel arrangements of parts which will hereinafter be fully described and particularly pointed out in the claims.

40 In the accompanying drawings, has been illustrated, a single and preferred form of the invention, it being, however, understood that no limitations are necessarily made to the precise structural details therein exhibited, but that changes, alterations and modifications within the scope of the claims may be resorted to when desired.

Figure 1 is a perspective view of the device in use as a crib.

50 Fig. 2 is a perspective view of the device in use as a chair.

Fig. 3 is a detail of the bolt for the tray.

The structure consists of a frame which is designed as a support and which includes 55 substantially rectangular sections 1-1, which are hinged together at their upper

ends at 2, whereby the sections can be adjusted relatively and spread apart to form a broad supporting base for a purpose to be hereinafter explained. The sections 1-1, 60 are adapted to be securely held against spreading beyond a fixed point by links 3-3, which are respectively connected with the sections and also connected with each other so that they can fold with the sections. The 65 joint between the links 3-3, is held against breaking downwardly below a horizontal position of the links by means of a stop lug 4, formed on one link and co-acting with the other of said links as clearly illustrated 70 in the drawing.

The frame consisting of the two sections 1-1, serves as a support for a central frame structure which includes an intermediate section made up of angle iron bars 5-5, 75 connected together by cross bars 6, and provided with sides 7, having a horizontal bar 8, in which a continuous longitudinal slot 9, is formed. The said intermediate section of the central structure has hinged connection 80 at 10, with a front frame comprising bars 11-11, connected together by a brace bar 12, and provided with an angular foot rest 13, for a purpose to be hereinafter explained.

The sides 7, above mentioned are provided 85 with pins 14, which are passed through substantially keyhole-shaped slots 15, in L-shaped side rails 16, the said rails having their opposite ends pivotally connected at 17, with the bars 11-11. When the said 90 rails 16, are associated with the pins 14, as shown in Fig. 1, the bars 11-11, are rigidly held in the same horizontal line with the bars 5-5. The bars 16, are adapted to be detached from the pins 14, whereby the 95 front frame can be adjusted to cause the bars 11-11, to hang at right angles to the bars 5. At this time, the said bars or rails 16, can be adjusted against the bars 5-5, turn-buttons 18 can be passed through the 100 slots 15, and said end frame will be then held thereby in a rigid position.

A second or rear frame is mounted at the opposite end of the intermediate frame section and it includes side bars 19-19, hinge- 105 edly connected at 20, to the bars 5. The said bars 19-19, are connected by a cross bar 21. The bars 19-19, have pivotal connection with L-shaped side rails 22, which are provided with cross heads 23, having sliding 110 connection on the bars 8, of the sides 7. Bolts 24, connect the inner ends of the rails

22, with said cross heads whereby various adjustments of this frame, can be made and retained. For instance, the construction is such that the frame can be rigidly supported 5 at right angles to the bars 5, and used as a chair-back, when the device is in the position shown in Fig. 2.

The bars 11—11, the bar 12, the bars 5—5, and the bars 21, and 19—19, are yieldingly 10 connected with a fabric bottom 25, upon which a suitable mattress can be arranged when the device is adjusted to form a crib. At any other time, the said fabric bottom forms a comfortable supporting means 15 which is adapted to properly accommodate itself to the body of the user.

The bars 5, are provided with sockets 26, which are adapted to receive the angular ends 27, of pivoted hooks carried by the 20 sides of the next adjacent frame section 1, of the support. When the hooks are engaged in the sockets, the convertible frame structure is held against swinging movement. This is desired when said frame 25 structure is used either as a chair or crib. In order that the convertible structure can be operatively supported for swinging movements, brackets 28, are fixedly mounted upon the top cross bar of one of the frame sections 1. These brackets support hangers 29, in the form of relatively long links whose lower ends have operative connection with the sides 7, hereinbefore described.

It now follows, as a result of the arrangement described, that the end frames of the convertible structure can be adjusted whereby to be held either rigidly in the same horizontal line with the bars 5, of the intermediate section or they may be adjusted to 40 extend respectively at opposite angles to said bars 5, as may be desired. When adjusted in chair form the foot rest 13, serves to permit the feet to be suitably rested thereon, while the head rest 30, which is carried by 45 the bars 19—19, is hinged whereby it may be adjusted to form a back or head rest.

When adjusted in bed form, the foot rest 13 becomes the foot board and the head rest

30 the head board, and at this time the side rails 16 and 22 form parts of the raised 50 side bars of the bed or crib, their angular ends standing adjacent the extremities of the headboard and foot board.

When the device is adjusted to form a chair, such as an infant's high chair, I provide a combined guard and tray 31, having an angular pin 32, designed to engage in a socket 33, in one of the sides 7, while at the opposite end of the tray, I provide a sliding bolt 34, which is adapted to be projected into 60 a keeper 35, in the other side member 7, as shown in Fig. 2.

What is claimed as new is:—

1. The herein described combination article of furniture comprising a central section 65 having upright sides slotted longitudinally near their upper edges and provided with pins near their lower edges, a head frame hinged to the central section, a foot frame also hinged to the central section, L-shaped 70 side bars pivoted at the ends of their shorter arms, to the outer sides of said frames, the ends of the longer arms of the front bars having slots engaging said pins when the foot frame is pendant, other pins on the sides 75 of the central section engaging said slots when the foot frame is raised, cross-heads sliding in the slots of said sides, and bolts connecting said cross-heads with the ends of the longer arms of the rear bars, for the 80 purpose set forth.

2. The herein described article of furniture convertible from a chair to a crib, the same comprising a main section having upright sides slotted longitudinally near their upper edges, a head frame hinged to said section, L-shaped side bars pivoted at the ends of their shorter arms to the corners of said frame and with their longer arms extending along the sides of the main section, 90 and bolts adjustably connecting the ends of said longer arms with points in the slots of the sides according as the article of furniture is to be used.

In testimony whereof I affix my signature. 95
DAVID G. PERLMUTTER.
